INVENTOR.

Arthur Atwater Kent
Cornelius L. Chret

BY

Lee ATTORNEY.

UNITED STATES PATENT OFFICE.

ARTHUR ATWATER KENT, OF ARDMORE, PENNSYLVANIA.

RADIO APPARATUS.

Application filed November 29, 1922. Serial No. 603,900.

My invention relates to apparatus for reducing in circuits, and particularly receiving circuits, of systems utilizing high frequency or radio frequency currents, as in 5 radio or analogous systems utilized for telegraphy, telephony or other purposes, the effects of undesired or parasitic currents locally produced in the apparatus, or caused or produced by static, atmospherics, strays 10 or other natural electrical disturbances, or due to electro-radiant or other energy, particularly when such effects are due to current or currents of frequency higher than the current or currents representing the desired 15 signal, message or control.

In accordance with my invention, when a magnetically inductive winding is utilized to convey signal or control oscillations or current to the detector or the input circuit of 20 a thermionic device, a condenser of suitably small capacity is connected across the winding or a suitable part thereof, whereby the parasitic or undesired currents, and particularly those of frequencies which are high 25 compared with the frequency of the oscillations or audio frequency current of the desired signal or control, are in effect short circuited or shunted from having an effect upon the detector or upon the input circuit 30 of the thermionic device.

Further in accordance with my invention, the aforesaid condenser or capacity may have for one of its plates or armatures the aforesaid winding itself, or a portion thereof, 35 another plate or armature of the capacity or condenser being a sheet of conductive material insulated from, but positioned close to, the winding.

My invention resides in the features of 40 structure, and arrangement of connections of the character hereinafter described and claimed.

For an illustration of one of the various forms my apparatus may take, reference is 45 to be had to the accompanying drawings, in which:

Fig. 1 is a diagram of radio receiving apparatus embodying my invention.

Figs. 2 and 3 are side and end views respectively, of a transformer embodying my 50 invention.

Fig. 4 is a vertical sectional view of two-stage amplifying apparatus embodying my invention,

Fig. 5 is a top plan view of a portion of 55 the structure shown in Fig. 4.

Fig. 6 is a vertical sectional view, some parts in elevation, of a transformer unit embodying my invention.

Fig. 7 is a top plan view of the structure 60 shown in Fig. 6 with the cover removed.

Fig. 8 is a top plan view of a cover such as indicated in Fig. 6.

Referring to Fig. 1, A represents an antenna or any other suitable absorption structure for absorbing from the natural media the electro-radiant energy representing a signal, message or other effect, or represents a conductor extending between stations and traversed by high frequency carrier waves. 70 The path of the antenna A includes the adjustable primary P of an oscillation transformer whose secondary is indicated at S. The primary P is connected to earth or other counter-capacity E, a variable condenser C, 75 connected in shunt to the tuning inductance P, serving to tune the circuit or path A to the frequency of the oscillations representing the desired signal, message or other effect. The condenser C is connected in parallel relation, as indicated, for relatively long waves, it being well understood in the art 80 that such condenser may be serially connected in the antenna path for tuning the same to short waves.

Shunting the secondary S is the variable condenser C¹ for tuning the circuit S, C¹ to the frequency of the oscillations representing the desired signal, message or other effect. V is an audion or similar thermionic vacuum 90 tube comprising the anode a, grid g, and filament or cathode f, the latter traversed by current from the battery s and controllable in magnitude by the rheostat r.

As well understood in the art, the grid g and cathode f may be connected, respectively, to opposite terminals of the condenser C¹. There may intervene in the circuit of the grid g the condenser C², shunted by the high resistance R. In the anode circuit of the 100 tube V is the source of current or battery B and the primary P¹ of a preferably audio frequency transformer whose secondary S¹ has its terminals connected, respectively, to the grid g and the cathode f of the amplifying audion or thermionic vacuum tube V¹, in whose anode circuit is included the aforesaid battery B and the primary P² of a sec-

ond preferably audio frequency transformer, the terminals of whose secondary S^2 are connected, respectively, to the grid g and cathode f of a further thermionic vacuum tube 5 amplifier V^2 , in the circuit of whose anode a is connected the aforesaid battery B and any suitable translating device T , which may be the winding or windings of a telephone receiver, or of any other signal-translating device, or may be the primary of a further transformer controlling directly a translating device, as a telephone receiver, or controlling the input circuit of a further amplifying vacuum tube. 10 15 The apparatus as thus far described is per se not my invention, and is well understood in the art of radio reception.

In accordance with my invention, however, I connect across the grid g and the cathode f of each of the vacuum tubes V^1 and V^2 , or across the terminals of the transformer secondaries S^1 and S^2 , a condenser of relatively small capacity, whereby there are short circuited, or shunted from the grids of the tubes V^1 , V^2 , all transient or continuous undulatory or oscillating currents of frequency relatively high as compared with the audio frequency of the undulations representing the desired signal, message or control, whereby the effects upon the ultimate translating device, as a signal-translating device or telephone T , of the higher harmonics of the oscillations representing the desired signal or message, the higher harmonics of other oscillations corresponding with or caused by absorbed electro-radiant energy, the relatively high frequency currents caused by atmospherics, static, strays, and the relatively high frequency currents corresponding with the frying, sizzling or other noises due to the interactions between the circuits of a thermionic tube or the reactions upon each other of the circuits of several thermionic tubes, are greatly reduced, and to such extent reduced that the desired signals or messages or controls may be heard or effected without accompaniment by parasitic noises due to the causes aforesaid, or other causes. 40 45 50 55 60

In the example illustrated in Fig. 1, one armature or plate of the by-passing or shunting condenser or capacity is the winding, or a portion of the winding, of the coil S^1 or S^2 itself, and the other plate or armature of the condenser or capacity is the sheet, plate, ribbon or other suitable structure K , of conducting material, as tin or other metallic foil, or equivalent, insulated from but placed suitably closely adjacent the winding S^1 .

As indicated in Fig. 1a, however, the by-passing or shunting capacity or condenser may be of the usual type comprising two plates or armatures, as in usual or ordinary condensers, as indicated at C^3 . And in Fig.

1b is indicated a crystal detector D shunted by the condenser C^3 , operating similarly, as in Figs. 1 and 1a.

By way of example, it may be stated that the capacity of the condenser whose armature is K , Fig. 1, may be of the order of from about .0002 microfarad to about .001 microfarad, which is a capacity many times smaller than the capacity which would be necessary to tune or approximately tune a circuit utilized for the frequency of the oscillations of the desired signal, message or control. For example, when receiving signals represented by electro-radiant energy having a wave length of about 360 meters, a condenser for coacting with either of the windings S^1 or S^2 to attune the resultant circuit to such wave length would be of the order of .0035 microfarad, or from about three and a half to about seventeen times the capacity of the condenser utilized in accordance with my invention.

By way of example, it may be stated that each of the primaries P^1 , P^2 may comprise 6000 turns of No. 38 Brown & Sharp gauge copper wire, disposed in fourteen layers, and the winding having an internal diameter of approximately one inch, and the winding having, for direct current, a resistance of about 1125 ohms. The secondary S^1 for such a primary is disposed within the primary, and may comprise 17,000 turns of the aforesaid No. 38 wire, disposed in forty layers, and having a direct current resistance of about 2000 ohms, the external diameter of the winding being approximately $\frac{3}{2}$ of an inch diameter, and having an internal diameter of about $\frac{15}{16}$ of an inch, the primary being wound upon a paper tube whose internal diameter is about $\frac{2}{3}$ of an inch and the secondary wound upon a paper tube whose internal diameter is about $\frac{3}{8}$ of an inch, filled with iron wire of the character hereinafter referred to.

Referring to Figs. 2, 3, 4 and 5, the iron wire core of the aforesaid transformer is indicated at I , and consists of a bundle of wires whose length is great compared with the length of the windings, the bundle divided into parts, as halves, and bent across the ends and extending longitudinally of the windings, as indicated at I^1 , the ends of the wires coming close to each other or overlapping each other, as indicated in Figs. 2 and 5, the magnetic circuit accordingly being substantially closed or of the hedgehog type. The core I is disposed within the paper or other insulating tube b , upon which is wound the secondary S^1 or S^2 , disposed within the paper or other tube c , upon which is wound the outer or surrounding primary P^1 or P^2 .

Overlying and insulated from the outer layer of each secondary winding S^1 , S^2 is the aforesaid sheet K , of conducting mate-

rial, as tin foil, or very thin sheet copper or other suitable material. For a transformer of the dimensions given in the foregoing example, the sheet K may be rectangular and of the order of one and one-eighth inches long and one inch wide, and when of tin foil may have a thickness of the order of .0003 inch, whereby it occupies extremely small space. There is then placed upon this condenser armature or plate K a tin, copper or other metallic ribbon d extending longitudinally of the secondary winding from the plate K, which may be placed adjacent one end of the secondary winding, to the opposite end of the winding.

To bind the plate K and the conducting strip d in contact therewith, and both in fixed position on the outside of the secondary winding, they are overlaid with a binder strip of gummed paper or other suitable material. After assembly of the secondary coil and the plate K within the tube c in operative relation to the outer primary winding, the strip d is bent outwardly across the end of the tube c and the insulating sheets of the primary winding to position, as indicated in Figs. 2, 3 and 5, and the conducting wire or lead e connecting to the terminal of the inner layer of the secondary winding is soldered or otherwise connected to the strip d, as indicated at h, Fig. 3. A wire or lead i is connected to the terminal of the outer layer of the secondary winding, and the lead j, and the bent-over end of the strip d and the attached lead e are bound in place by a band j, of adhesive tape of the like, Fig. 2. The primary leads or connections k and m are preferably brought out of the opposite end of the primary, and may be bound by the adhesive tape or like member n. From the foregoing description, it will be apparent, therefore, that the condenser plate or armature K is insulated from but disposed near a layer of the secondary winding and is electrically connected with the remote terminal of such winding, this being feasible or practicable because between that layer of the secondary winding which acts as the condenser plate or armature complementary to the armature or plate K and the terminal of the remote layer there are many turns, offering both high inductance and considerable resistance, which prevents short circuiting the condenser, though there is in effect connected across its armatures a high inductance, or a resistance, or a high impedance.

As indicated in Figs. 4 and 5, the transformers with their condenser armatures or plates K may be disposed within a sheet iron or steel or other metallic casing F, having the wall or cover G of insulating material, for example, molded condensite or bakelite or the like, upon which are disposed the sockets H, adapted to receive and hold vac-

uum tube devices, as V, V¹, or V¹, V², the usual contacts, adjustable resistance for filament, etc., being carried by the cover G, as well as the usual binding posts for suitably connecting the apparatus in circuit. By 70 preference, the transformers may be reversely positioned, as indicated in Fig. 5; that is, with symmetrically or similarly constructed transformers they are disposed within the casing with their similar parts 75 lying in opposite directions. The transformer units may be held in the casing F in any suitable way. As indicated, however, they are embedded in congealed bituminous, asphaltic or other insulating or binding material J.

Referring to Figs. 6, 7 and 8, there is shown a transformer unit per se housed within a metallic, fibrous, paper or other casing M, having the base o. Extending across the top of the transformer unit and frictionally engaging the inside walls of the casing M is the wooden or other member p, forced down upon or holding the transformer unit in place. After the application of the member p, there may be flowed into the container M over the top of the transformer unit and around the member p the bituminous, asphaltic or other insulating or binding material J, which solidifies 80 and binds and insulates the parts. Surmounting the casing M is the cap cover N, preferably of insulating material, as molded condensite, bakelite or the like, carrying binding posts q, t, u and v, of which q and t 85 are the primary binding posts to which are connected the aforesaid primary leads k and m, extending upwardly through the cover N and attached to the binding posts. Similarly, to the posts u and v are connected the aforesaid secondary and condenser leads e and i, extending through the cover N and attached to the binding posts. These leads 90 may be connected to the binding posts, and the cover then placed and secured in position after introduction of the material J into the casing M.

As indicated in Fig. 7, the core wires extending across the end and along the outside of the unit are more widely distributed over the surface of the unit than in the case of Figs. 3 and 4.

By the utilization of the condenser structure whose armature is K in connection with a winding, the parasitic noises, such as hisses, sizzling, frying, crackling and the like are greatly reduced and in some instances eliminated, making reception of radio telephonic messages, and telegraphic or other signals, 100 more agreeable, and rendering the signals or messages more clearly and readily intelligible or distinguishable.

Particularly in radio receiving apparatus utilizing vacuum tubes as indicated in Fig. 1, there occur within the receiving apparatus 105

itself, and independently of received signal energy or static effects, undulatory or transient current effects of high frequency causing frying, crackling and similar noises which interfere with the desired signals or messages. But by the use of a condenser of small capacity in the relations herein described, these undesired effects are greatly reduced or eliminated.

- 10 In general, the magnitude of the capacity of the condenser whose armature or plate is K , is smaller than the capacity of a condenser which would attune the circuit to the frequency of the received energy or 15 to the frequency of the oscillations representing the desired signal or message. More particularly, the magnitude of the capacity in accordance with my invention is a fraction, and preferably a small fraction of the 20 capacity of the condenser which would be utilized for tuning the circuit to the frequency of the oscillations representing the desired signal or message.

By employment of a condenser of small 25 capacity as described, there is offered by the condenser easy passage for decadic or sustained current waves or oscillations of a frequency materially higher than the frequency of the oscillations representing the 30 desired signal or message, or, in general, easy passage for current, whether undulatory or aperiodic, having a materially steeper wave front than the oscillations representing the desired signal or message. And 35 on the other hand, the capacity of the condenser is so small that the condenser offers relatively high opposition to passage therethrough of currents of the frequency of the oscillations or audio frequency current representing the desired signal or message. In 40 consequence, the oscillations or current representing the desired signal or message are not to any substantial or serious degree bypassed through the condenser, but are 45 caused to affect to desired and usual degree the potential of the grid g of a vacuum tube, as in Fig. 1, or the detector D , as in Fig. 1^b.

What I claim is:

- 50 1. The combination with a winding having a plurality of layers, of a condenser armature disposed in capacitative relation to one of said layers and forming therewith a condenser, and a connection from 55 said armature to a remote terminal of another of said layers.

2. The combination with a winding having a plurality of layers, of a condenser armature connected to one layer of said winding and disposed in capacitative relation to another layer of said winding remote from 60 said connection and forming with said portion of said winding a condenser.

65 3. The combination with a winding having a plurality of layers, of a condenser ar-

mature comprising a thin sheet of conducting material disposed in close relation to and insulated from the outer layer of said winding and forming with said winding a condenser.

4. The combination with a winding having a plurality of layers, of a condenser armature comprising a thin sheet of conducting material connected to an inner layer of said winding and disposed in close relation to and insulated from the outer layer of said winding and forming therewith a condenser.

75 5. The combination with a winding for coupling thermionic devices, of a condenser armature connected to a said winding and disposed in capacitative relation to a portion of said winding remote from said connection and forming therewith a condenser.

80 6. The combination with a transformer for coupling thermionic devices, of a condenser armature connected to the secondary winding of said transformer and disposed in capacitative relation to a portion of said winding remote from said connection and forming therewith a condenser.

85 7. The combination with an audio frequency transformer for coupling thermionic devices, of a condenser bridging the terminals of a winding of said transformer, said condenser having as armatures said winding and a condenser armature disposed in capacitative relation thereto.

90 8. The combination with an audio frequency transformer for coupling thermionic devices, of a condenser bridging the terminals of the secondary winding of said transformer, said condenser having as armatures said winding and a condenser armature disposed in capacitative relation thereto.

95 9. The combination with an audio frequency transformer for coupling thermionic devices, of a condenser armature consisting of a thin sheet of conducting material disposed closely adjacent to and insulated from a winding of said transformer and forming with said winding a condenser.

100 10. The combination with an audio frequency transformer for coupling thermionic devices, of a condenser armature connected to a winding of said transformer and disposed in capacitative relation with a portion of said winding remote from said connection.

105 11. The combination with an audio frequency transformer for coupling thermionic devices, of a condenser armature connected to the secondary winding of said transformer and disposed in capacitative relation with a portion of said winding remote from said connection.

110 12. A transformer for coupling thermionic devices, comprising primary and secondary windings, one of said windings disposed within the other, and a condenser ar-

70

- mature disposed between said windings and in capacitative relation to one of said windings and forming therewith a condenser. 35
13. A transformer for coupling thermionic devices, comprising primary and secondary windings, the secondary winding disposed within the primary winding, a condenser armature positioned between the secondary and primary windings and disposed in capacitative relation to said secondary winding and forming therewith a condenser. 40
14. The combination with a winding comprising a plurality of layers, of a condenser armature consisting of a sheet of conducting material disposed in close relation to a layer of said winding and connected to a remote layer of said winding. 45
15. The combination with a winding, of a condenser armature disposed in capacitative relation to said winding and forming therewith a condenser, and a high impedance connection between said armature and said winding. 50
16. The combination with a coil, of a second coil surrounding said coil, and a condenser armature disposed between said coils and forming with at least one of them a condenser. 55
17. The combination with a transformer for coupling thermionic devices, a winding of said transformer having a plurality of layers, of a condenser armature disposed in
- capacitative relation to one of said layers and forming therewith a condenser, and a connection from said armature to a remote terminal of another of the layers of said winding. 60
18. The combination with a transformer for coupling thermionic devices, a winding of said transformer having a plurality of layers, of a condenser armature disposed in capacitative relation to one of said layers and forming therewith a condenser, and a connection from said armature to a remote terminal of another of the layers of said winding, said transformer having a second winding between which and said first named winding said condenser armature is disposed. 65
19. The combination with a winding, of a condenser armature disposed in capacitative relation with a portion only of said winding adjacent one terminal thereof and forming therewith a condenser, and a connection from said armature to the remote terminal of said winding, whereby there exists high impedance between said remote terminal of said winding and that portion thereof coacting with said armature to form a condenser. 70

In testimony whereof I have hereunto affixed my signature this 27th day of November, 1922.

ARTHUR ATWATER KENT.

Certificate of Correction.

It is hereby certified that in Letters Patent No. 1,597,901, granted August 31, 1926, upon the application of Arthur Atwater Kent, of Ardmore, Pennsylvania, for an improvement in "Radio Apparatus," errors appear in the printed specification requiring correction as follows: Page 2, line 47, for the misspelled word "wtihout" read *without*; same page, line 61, strike out the paragraph beginning with the word "As" and all to and through the words "in Figs. 1 and 1^a," in line 68; page 3, line 37, for the word "of," second occurrence, read *or*; same page, line 97, after the word "cap" insert the word *or*; page 4, line 31, for the word "current" read *currents*, and line 84, for "therewth" read *therewith*; and that the said Letters Patent should be read with these corrections therein that the same may conform to the record of the case in the Patent Office.

Signed and sealed this 26th day of October, A. D. 1926.

[SEAL.]

WM. A. KINNAN,
Acting Commissioner of Patents.
